(57) CLAIM

The ornamental design for a cart, as shown and described.

DESCRIPTION

FIG. 1 is a first perspective view of the cart showing my new design;

FIG. 2 is a second perspective view thereof;

FIG. 3 is a front view thereof;

FIG. 4 is a rear view thereof;

FIG. 5 is bottom view thereof;

FIG. 6 is a top view thereof;

FIG. 7 is a left side view thereof; and,

FIG. 8 is a right side view thereof.

The broken lines shown in the figures are included for the purpose of illustrating portions of the cart and form no part of the claimed design.

1 Claim, 8 Drawing Sheets
